UNITED STATES PATENT OFFICE.

WALTER S. DICKSON, OF MILWAUKEE, WISCONSIN.

SOUND DIRECTOR.

Application filed February 17, 1926. Serial No. 88,857.

My invention is a means for directing sound and is to be used in connection with telephone transmitters, phonograph recording instruments and radio microphones, in 5 the transmission, recording and broadcasting of sound.

The invention includes the provision in 10 means for directing sound, of sound exhausts of sufficient number as may be required and of various mechanical construction, and have as their purpose the prevention of the reaction of sound vibrations, in their rebound from the transmitting, recording or broadcasting diaphragms.

15 By this means sound or sound vibrations from the point or moment of their creation, are directed through the chamber of this device, towards the transmitting, recording or broadcasting apparatus.

20 To this end the invention includes a chamber which may vary in form and shape from spherical or ovoidal shapes, to the form of double truncated cones of equal or unequal angles or length that are joined at the base.

25 Sound exhausts may be in the form of 70 openings or slots in the walls of the device, located at or near its outlet, or at or near its point of widest diameter or both, or at any point within the walls that experiment 75 may determine, and may even be constructed so as to make a complete or partial separation of the walls of the chamber into two or more sections. Sound exhausts not only prevent the reactions of sound vibrations in

30 their rebound from the transmitting, recording or broadcasting microphones or apparatus, thereby eliminating false overtones in the recorded or transmitted sound, but effectively break the air cushion within the 80 chamber of the device, which interferes with perfect conduction.

I have illustrated in the accompanying drawings diagrammatic forms of the invention in which:—

45 Figure 1 is a sectional elevation of a telephone mouth-piece constructed according to my invention.

Fig. 2 is a like view of a modified form of mouthpiece.

50 Fig. 3 is a like view of another modification.

Fig. 4 is a like view of another modification.

55 Fig. 5 is a like view of another modification.

Fig. 6 is a like view of another modification.

Fig. 7 is a diagrammatic view, partly in section, of an individual recording horn embodying my invention.

Fig. 8 is a like view of a recording laboratory.

Fig. 9 is an enlarged view of the pivoted shutters used in the recording laboratory of Fig. 8.

In these drawings I have shown the directing device to consist of a shell 10 as of two truncated cones with their large bases adjacent but spaced apart to allow for sound exhausts 11. Obviously such exhausts may extend either partially around the periphery of the shell or completely so. A screw threaded portion 12 is provided to secure the device to the ordinary telephone transmitter.

The same principle is followed in constructing the devices of Figs. 2 to 8, except that slight modifications of shape are utilized. These variations under certain circumstances, have been found to be advantageous.

In Fig. 7 the shell of the device has been shown to be provided with a mouthpiece 13 for individual recording on the recording machine 14.

In Fig. 8 a laboratory has been constructed on the same principle, large enough to accommodate a band or orchestra. In this case additional exhausts 15 are provided, as shown.

Present methods of transmission, recording and broadcasting sound, permit sound vibrations to occur in every direction from the point of their creation and but segments of these spherical vibrations act upon the transmitting, recording or broadcasting diaphragms or apparatus.

By this device sound vibrations from the moment of their creation, are directed forward and are permitted to expand only within the confines of the device, to the point of its greatest diameter which is its point of greatest amplification and from there they are modified by the reducing form of the walls of the device in their transmission, to the transmitting, recording or broadcasting diaphragms or apparatus.

This sound director, when applied to telephone transmission, is substituted for the mouthpiece of the transmitter. It may be spoken into directly, or the mouth may be

held at a distance, up to six inches from the device, without losing its efficiency. When spoken into directly, the lightest whispered conversation is perfectly transmitted and clearly audible to the person receiving the message.

In its application to phonograph recording and radio broadcasting, the sound director may be either a small device constructed 10 to receive and transmit sound, or it may be constructed in the form of a chamber, large enough at one end to contain a band or orchestra, in which the sound is amplified to the point of the widest diameter of the chamber, and from there modified by the reducing 15 diameter of the walls in their continuation to the recording diaphragms or apparatus, or broadcasting microphones.

A sound exhaust as close as possible to the 20 recording or transmitting diaphragm or apparatus to exhaust the greater part of the recorded sound at or close to the point of record is absolutely necessary in a device where sound is confined in its transmission 25 to recording or transmitting apparatus.

Of nearly equal importance is the sound exhaust at or near the widest point of the shell of the ogival or double conical sound directing device. This exhaust effectively 30 breaks the air cushion within the chamber and permits the circulation of the air within it and the free forward movement of sound waves to and beyond the point of their greatest amplification, to the point of record.

Sound exhausts may be of any number as 35 the volume and intensity of sound being recorded or transmitted may demand but for maximum efficiency must be constructed with their openings in line with the angle of sound 40 deflection from the recording or transmitting apparatus. Whether in either section of the directing chamber they must lead diagonally through the walls of the chamber towards the recording point of sound in order to 45 accept and exhaust from the recording or transmitting apparatus in direct line of their rebound or deflection, the recorded sound waves.

In this construction of sound exhausts the 50 inner edge overlaps the outer edge and in effect makes the wall of the chamber continuous so as to offer no escape or effective break to sound as it passes forward to the recording or transmitting apparatus.

Sound exhausts although they may be constructed as to make a complete separation

of the director into two or more parts will generally be formed as a series of slots cut diagonally through the shell of the director towards the recording point. This 60 series of cuts will be made around the circumference of the shell at any distance from the recording apparatus.

It is also vitally important that the shape or shapes of the sound director, not only 65 direct sound waves forward, but permit of their amplification in the ratio of their ultimate reduction, in order to produce an efficient device.

Having thus described my invention, what 70 I claim is:

1. The combination with an instrument for the recording or transmission of sound, of a shell having reduced ends and an enlarged center, one end being adapted for connection with the instrument and the other adapted to receive the full sound to be recorded so as to confine the sound to the shell, the construction being such as to first allow the sound waves created to enlarge, and then 80 gradually reduce them as they pass to the instrument, and ports in the wall of said shell through which sound may be exhausted. 75

2. For use in combination with an instrument for recording or transmitting sound, a shell having an enlarged center and reduced ends, the sound being created in one of the reduced ends, and passing out of the opposite end which is placed in proximity to a recording or transmitting instrument, 85 the enlarged central section permitting the enlargement of the sound waves, and a reduced end the subsequent gradual reduction thereof, and ports in the wall of said shell through which sound may be exhausted. 95

3. In combination, an instrument for the recording or transmission of sound, means within which to confine sound from its point of creation to the instrument, said means being spaced apart from the instrument, and 100 ports in the wall of said shell through which sound may be exhausted.

4. For use in combination with an instrument or apparatus for recording or transmitting sound, a shell having an enlarged center and reduced ends having a number of openings covered by pivoted shutters to be used to exhaust sound already recorded or transmitted and prevent its recurrence in the recording of new sound. 105

In testimony whereof, I affix my signature.

WALTER S. DICKSON.
